UNITED STATES PATENT OFFICE.

GROVER LOENING, OF NEW YORK, N. Y.

CONSTRUCTION FOR AIRPLANE FLOATS.

Application filed October 21, 1927. Serial No. 227,733.

The invention has to do with airplane floats, including the hulls of flying-boats, the floats of seaplanes, and wing pontoons. The invention has for its object a composite wood and metal construction for such floats, possessing advantages over prior all-metal or all-wood floats, and a special object is to avoid corrosion in such a construction.

The construction involves a sheet metal, 10 duralumin covering on a wooden frame, the advantage of this, in part, being that the wood frame gives resilience, while the excessive absorption of water which greatly increases the weight of wood floats is avoided. 15 The covering is secured to the wooden strength members by bolts, which is important because bolts can be heat-treated against corrosion in salt-water and will not lose their heat-treatment on application, as do rivets 20 which have to be hammered. Moreover, bolts can be thoroughly coated, prior to application, with a composition protective against corrosion, which they will retain after incorporation in the float.

25 The tendency of metal floats to corrode would be increased in a combination of wood and metal, due to the fact that the wood, though on the inside, becomes more or less dampened, and the action of dampened wood on duralumin is very bad. Hence the importance of the protection of the bolts, not only where their heads project on the outside but also where they lie in the wood.

As a further and very vital protection I 30 provide that the covering and the frame members shall be separated, by interposing between them a layer of fabric impregnated with marine glue, tar compound or other material having similar lasting waterproof qualities. This layer prevents any moisture in the wood, which may come from water splashing into the hull or seeping into pontoons, from acting on the sheets of the cover-

ing. The bolts themselves are protected by their coatings, and in order to prevent corrosion by electrolysis between them and the covering they, like the sheets, are made of duralumin.

The accompanying drawing is a fragmentary sectional perspective view of a construction sufficient to illustrate the invention.

The member 2 is one of the wooden strength members, for example, a chine longeron, representing the framework. Portions of two of the sheets of the metal covering are marked 55 3, these sheets being secured to the member 2 by bolts 4. These bolts have been previously coated all over, as by dipping, with enamel, marine glue, bitumastic or other compound adapted to protect them when in place against 60 the corrosive action of salt-water. The bolts are of duralumin, and may be understood to have been heat treated to increase their ability to withstand corrosion.

The joint between the sheets 3 is covered by 65 a finishing strip 5, and between the finishing strip and the plates and protecting the joint is a layer of impregnated fabric 6.

The separation layer 7, heretofore referred to, lies between the duralumin sheets 3 and the frame, completely separating the sheet metal from the wood. While this element may and preferably does aid the layer 6 in making the joint tight against entrance of 70 water, its special function is to protect against 75 dampness on the inside settling in the wood and thence attacking the metal.

What I claim as new is:

Construction for airplane floats comprising the combination of wood frame members, 80 an outer metal skin, bolts for securing said metal skin to said frame members, and said skin being entirely separated from said frame members by a layer of protecting material.

GROVER LOENING.
